UNITED STATES PATENT OFFICE

ESEK BUSSEY, OF TROY, NEW YORK.

DESIGN FOR A COOKING-STOVE.

Specification forming part of Design No. 6,271, dated November 26, 1872.

To all whom it may concern:

Be it known that I, ESEK BUSSEY, of Troy, in the county of Rensselaer, and State of New York, have invented a Design for Stoves; and the following description, taken in connection with the accompanying drawing herein-after referred to, forms a full and exact specification, wherein is set forth the nature of the design, by which the same may be distinguished from others of a similar class, together with such parts thereof as are claimed as new and are desired to be secured by Letters Patent of the United States.

The nature of my design is fully represented in the accompanying drawing, which illustrates the same and forms a part of the specification thereof.

The drawing is a view in perspective, showing the front end of the stove and one side thereof. The side presents two doors, the

larger of which is the oven-door, having the center ornament A shown, and the ornamental border B. The smaller door upon the side of the stove is provided with the center ornament c, and ornamental border d. The front of the stove, above the hearth, presents two doors, each of which has ornamental edge-borders, e.

The ornaments with which the feet of the stove are provided are fully shown in the drawing.

Having described my design, I claim—
The design for stoves, as shown.

In testimony that I claim the foregoing I have hereunto set my hand and seal this 30th day of September, 1872.

ESEK BUSSEY. [L. S.]
